UNITED STATES PATENT OFFICE.

JAMES HENRY BRADY, OF LOUISVILLE, KENTUCKY.

DESIGN FOR A CAN-OPENER.

49,326.

Specification for Design.

Patented July 11, 1916.

Application filed January 31, 1916. Serial No. 75,455. Term of patent 14 years.

To all whom it may concern:

Be it known that I, JAMES HENRY BRADY, a citizen of the United States, residing in Louisville, county of Jefferson, and State of Kentucky, have invented a new, original, and ornamental Design for Can-Openers, of which the following is a specification, reference being had to the accompanying drawing, forming a part thereof.

In the drawing, Figures 1, 2, 3, and 4 show a rear, side, front and end elevation respectively of my new design for a can opener.

I claim:

The ornamental design for a can opener, as shown.

JAMES HENRY BRADY.
